CLAIM

The ornamental design for a storage box set, as shown and described.

DESCRIPTION

FIG. 1 is a perspective view of all embodiments of a storage box set showing my new design;

FIG. 2 is a first perspective view of the first embodiment thereof;

FIG. 3 is a second perspective view of the first embodiment thereof;

FIG. 4 is a front elevation view of the first embodiment thereof;

FIG. 5 is a rear elevation view of the first embodiment thereof;

FIG. 6 is a left side elevation view of the first embodiment thereof;

FIG. 7 is a right side elevation view of the first embodiment thereof;

FIG. 8 is a top plan view of the first embodiment thereof;

FIG. 9 is a bottom plan view of the first embodiment thereof;

FIG. 10 is a first perspective view of the second embodiment thereof;

FIG. 11 is a second perspective view of the second embodiment thereof;

FIG. 12 is a front elevation view of the second embodiment thereof;

FIG. 13 is a rear elevation view of the second embodiment thereof;

FIG. 14 is a left side elevation view of the second embodiment thereof;

FIG. 15 is a right side elevation view of the second embodiment thereof;

FIG. 16 is a top plan view of the second embodiment thereof;

FIG. 17 is a bottom plan view of the second embodiment thereof;

FIG. 18 is a first perspective view of the third embodiment thereof;

FIG. 19 is a second perspective view of the third embodiment thereof;

FIG. 20 is a front elevation view of the third embodiment thereof;

FIG. 21 is a rear elevation view of the third embodiment thereof;

FIG. 22 is a left side elevation view of the third embodiment thereof;

FIG. 23 is a right side elevation view of the third embodiment thereof;

FIG. 24 is a top plan view of the third embodiment thereof;

(Continued)

FIG. 25 is a bottom plan view of the third embodiment thereof;
 FIG. 26 is a first perspective view of the fourth embodiment thereof;
 FIG. 27 is a second perspective view of the fourth embodiment thereof;
 FIG. 28 is a front elevation view of the fourth embodiment thereof;
 FIG. 29 is a rear elevation view of the fourth embodiment thereof;
 FIG. 30 is a left side elevation view of the fourth embodiment thereof;
 FIG. 31 is a right side elevation view of the fourth embodiment thereof;
 FIG. 32 is a top plan view of the fourth embodiment thereof;
 FIG. 33 is a bottom plan view of the fourth embodiment thereof; and,
 FIG. 34 is an enlarged view of the selected portion 34 in FIG. 26.

The dash-dash broken lines shown in the drawings depict portions of the storage box set that form no part of the claimed design. The dot-dash broken lines in FIGS. 26 and 34 illustrate the periphery of the enlarged views of the storage box set and form no part of the claimed design.
